FIG.1

FIG.2

FIG.3

FIG.4

FIG.5

FIGURE 1 is a front elevational view of a carving fork showing my new design.

FIGURE 2 is a side elevational view thereof.

FIGURE 3 is a rear elevational view thereof.

FIGURE 4 is a transverse sectional view upon the line 4—4 of FIGURE 1.

FIGURE 5 is a transverse sectional view upon the line 5—5.

The characteristic features of my design reside in the carving fork disclosed of the particular handle portion formed of plastic plaques having metallic bands on each side thereof connecting the end cap or piece with the integral tine supporting shank in combination with the specific angled and curved tines, all as shown.

I claim:

The ornamental design for a carving fork, as shown and described.
